Attorney

UNITED STATES PATENT OFFICE.

GRACE N. MONROE, OF LYNCHBURG, VIRGINIA.

TYPEWRITER ATTACHMENT.

Application filed August 13, 1924. Serial No. 731,843.

To all whom it may concern:

Be it known that I, GRACE N. MONROE, a citizen of the United States, residing at Lynchburg, in the county of Campbell and 5 State of Virginia, have invented certain new and useful Improvements in a Typewriter Attachment, of which the following is a specification.

This invention relates to improvements 10 in typewriter attachments and has for its principal object to provide a means whereby a plurality of letter heads in roll form are adapted to be supported in the rear of the platen roller of a typewriter carriage for 15 feeding or delivering the letter heads to the platen, an additional roller being provided for receiving the letter heads in roll form after the same have been typewritten whereby considerable time and labor will be saved 20 by a typist in writing a number of letters.

A further object of the invention is to provide a typewriter attachment of the above mentioned character, which is of such construction as to obviate the necessity of 25 having to place the plain letter sheet in the typewriter after one sheet has been typewritten, the letter heads or sheets being in roll form and separated by perforations whereby the same may be readily separated 30 after each of the letters have been written.

A further object of the invention is to provide a typewriter attachment of the above mentioned character, which is of such construction as not to interfere with the operation 35 of the typewriter or the shifting of the carriage.

A still further object of the invention is to provide a typewriter attachment of the above mentioned character, which is simple 40 in construction, inexpensive, strong and durable and furthermore adapted for the purposes for which it is designated.

Other objects and advantages of this invention will become apparent during the 45 course of the following description.

In the accompanying drawing forming a part of this specification and in which like numerals designate like parts throughout the same:

50 Figure 1 is a top plan view of my improved attachment showing the same associated with a typewriter.

Figure 2 is a side elevation thereof, and 55 Figure 3 is the fragmentary rear elevation of the attachment.

In the drawing wherein for the purpose

of illustration is shown the preferred embodiment of my invention, the numerals 1 and 2 designate a pair of supporting standards which extend upwardly in the rear of 60 a typewriter, which may be of any conventional construction, and are supported in spaced relation thereto adjacent the end of the same by means of the attaching brackets 3 and 4. The standards are also spaced 65 from the ends of the typewriter A in the manner clearly illustrated in Figure 1 of the drawing for the purposes hereinafter to be more fully described. Extending transversely across the standards 1 and 2 and 70 secured at their respective ends thereto are the upper and lower shafts or rods 5 and 6 respectively.

Supported on the lower shaft 6 and adapted for slidable movement thereon is the roller 7. An arm 8 is secured to one end of the roller 7 and at its opposite end to the carriage B of the typewriter so as to permit the roller 7 to move longitudinally on the shaft 6 simultaneously with the sliding 80 movement of the carriage B on the typewriter A. Wound around the roller 7 is a roll of paper designated generally by the numeral 9 and the same comprises a number of letter heads or sheets, each of which 85 is separated from the other by means of perforations and as the same is well known in the art, a further detailed description thereof is not thought necessary. As is clearly illustrated in Figure 2 of the drawing, 90 the roller 7 and the roll of paper 9 thereon is supported on the shaft 6 above the platen C so that the paper may be delivered to the platen in such a manner as to position each of the letter heads in the proper 95 manner over the platen.

A roller 10 similar to the roller 7 is adapted for slidable movement on the upper shaft 5 and operates simultaneously with the rollers 7 on the shaft 6 through the medium of 100 the connection 11 between one end of the roller 10 and the outer end of the arm 8 which is connected at its opposite end to the carriage B. It is of course to be understood that the shafts 5 and 6 respectively 105 are of such length as to permit the rollers 10 and 7 respectively to slide thereon for a sufficient distance in order to enable the carriage B of the typewriter to travel its full length.

Loosely mounted on the roller 10 is the sleeve 12 and the purpose thereof will be

presently described. A sprocket wheel 13 is secured on one end of the sleeve 12 in the manner as illustrated in Figure 1 and is in alignment with a similar sprocket wheel 14 which is carried by the shaft on which the platen C is mounted. A sprocket chain 15 is trained over the aligning sprocket wheels 13 and 14 and this construction affords a means whereby the sleeve 12 may be rotated on the roller 10 simultaneously with the rotation of the platen C caused by the shifting of the shift lever in the manner well known in the art. The provision of the sleeve 12 on the roller 10 is to provide a means for receiving the latter sheets after the same have been typewritten and each of the sheets will be wound around the sleeve until the roll of paper has been exhausted or entirely used up. For the purpose of initially securing the free edge of the roll of paper on the sleeve 12, the spring clips 16 are provided and the construction of the same is more clearly illustrated in Figure 1.

The operation of my improved attachment is obvious from the construction illustrated and it will be readily understood that a roll of letter heads may be placed on the roller 7 and the free ends of the roll of paper brought over the platen and attached to the sleeve 12 which is loosely mounted on the roller 10. After all of the letter sheets have been typewritten, and rolled around the sleeve 12, the same may be detached therefrom and each sheet separated from each other by reason of the fact that the sheets are secured together by rows of perforations.

The provision of an attachment of the above mentioned character, enables the same to be easily and readily associated with any of the well known typewriters now in use and will not in any way interfere with the operation of the typewriter or the shifting of the carriage.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. A typewriter attachment comprising in combination with the movable carriage of a typewriter including the platen thereof, a pair of standards secured in spaced relation on the rear of the typewriter, upper and lower shafts extending transversely across the standards, a roller slidably on the lower shaft, means for connecting the roller to the carriage whereby the same is adapted for movement therewith, a roll of perforated paper carried by said roller, said paper adapted to extend over the platen, an ad-

ditional roller supported on the upper shaft and disposed above the platen, a connection between the roller on the upper shaft and the roller on the lower shaft whereby the same are adapted for simultaneous sliding movement on the respective shafts, and means carried by the roller on the upper shaft for receiving the free end of the roll of paper and around which the same is adapted to be wound, means being associated with the last mentioned means and the platen for rotating the roller on the upper shaft simultaneously with the rotation of the platen.

2. A typewriter attachment comprising in combination with the movable carriage of a typewriter and including the platen thereof, a pair of standards supported in spaced relation on the rear of the typewriter, upper and lower shafts supported transversely on the standards, a roller slidably mounted on the lower shaft, a connection between the roller and the carriage, a roll of perforated paper on said roller, said paper adapted to extend over the platen, a roller slidably supported on the upper shaft and disposed above the platen, a connection between the upper roller and lower roller whereby the same are adapted for simultaneous sliding movement on the respective shafts, a sleeve loosely mounted on the upper roller and providing a means for receiving the free end of the roll of paper and over which the same is adapted to be wound, and means for rotating the sleeve simultaneously with the rotation of the platen.

3. A typewriter attachment comprising in combination with the movable carriage of a typewriter and including the platen thereof, a pair of standards supported in spaced relation on the rear of the typewriter, upper and lower shafts supported transversely on the standards, a roller slidably mounted on the lower shaft, a connection between the roller and the carriage, a roll of perforated paper on said roller, said paper adapted to extend over the platen, a roller slidably supported on the upper shaft and disposed above the platen, a connection between the upper roller and lower roller whereby the same are adapted for simultaneous sliding movement on the respective shafts, a sleeve loosely mounted on the upper roller and providing a means for receiving the free end of the roll of paper and over which the same is adapted to be wound, means for rotating the sleeve simultaneously with the rotation of the platen, said means comprising a sprocket wheel carried by the upper roller, an aligning sprocket associated with the platen, and a sprocket chain trained over said sprocket wheel.

In testimony whereof I affix my signature.

GRACE N. MONROE.
